UNITED STATES PATENT OFFICE.

CHARLES E. MARTIN, OF HINTON, VIRGINIA, ASSIGNOR OF ONE-THIRD TO GEORGE P. FRITZ AND ONE-THIRD TO CHARLES R. COLE, BOTH OF CHICAGO, ILLINOIS.

SPIKE OR NAIL.

1,131,149.

Specification of Letters Patent. Patented Mar. 9, 1915.

Application filed April 16, 1914. Serial No. 832,337.

To all whom it may concern:

Be it known that I, CHARLES E. MARTIN, a citizen of the United States, and a resident of Hinton, in the county of Rockingham and State of Virginia, have invented certain new and useful Improvements in Spikes or Nails; and I do hereby declare that the following is a full, clear, and exact description thereof, reference being had to the accompanying drawings, and to the letters of reference marked thereon, which form a part of this specification.

This invention relates to improvements in spikes or nails and consists of the matters hereinafter described and more particularly pointed out in the appended claims.

The object of the invention is to provide a spike or nail which may be driven into a block or piece of wood without tearing or splintering the fibers, which will cut, rather than break its way through the fibers of the wood to its final seat and which, when driven home, will be firmly locked against withdrawal.

A spike or nail made in accordance with my invention is especially advantageous for use where the greater strain on it is exerted in a direction to withdraw it as, for example, in the case of a railroad spike, where the waving, vertical vibratory movement of the rails when a train passes over the track exerts an enormous force tending to pull the spikes from the ties.

The many advantages of my invention will appear as I proceed with my specification.

In the drawings: Figure 1 is a perspective view of a nail embodying the novel features of my invention. Fig. 2 is an elevation on an enlarged scale of the part of the nail at or near the point. Fig. 3 is an elevation of the same part of the nail shown in Fig. 2, the plane of the elevation being at right angles to that of the view shown in Fig. 2. Fig. 4 is a view representing a transverse section through Fig. 2 in a plane indicated by the line 4-4 of Fig. 2, with the nail shown as it appears when the point is first entering the block or piece of wood into which it is driven. Fig. 5 is a similar section showing the nail as it appears with reference to the fibers of the piece or block into which it is driven when it has finally been driven home. Fig. 6 is a view representing a transverse section through Fig. 2 in a

plane indicated by the line 6-6 thereof. Fig. 7 is a vertical section through Fig. 2 in a plane indicated by the line 7-7 thereof.

I have shown my invention in the accompanying drawings embodied in a wire nail, as being the simplest example for illustrating its application. It is to be understood, however, that the invention may be embodied in any form of nail or spike that is to be driven and which is made of any suitable or desired material.

Referring now more particularly to the drawings, 10 indicates the shank of a wire nail; and 11, its head. The shank 10 is made of the usual rounded form and preferably with a smooth surface throughout its length. I provide the shank 10 of the nail with spiral wing blades 12, 13, which are disposed radially, and in substantially the same diametric plane on opposite sides of the said shank. The spiral wing blades 12, 13 are wide at the top and diminish in width toward the point-end of the nail, having edges 12^a, 13^a which are inclined toward the point-end of the nail, and which are more or less sharpened to constitute cutting edges. As shown in the drawings which illustrate the preferred construction, the wing blades are placed opposite each other at the point-end of the nail, and their cutting edges 12^a, 13^a merge together to provide the nail-point 14 which is adapted to penetrate the wood into which the nail is to be driven.

12^b, 13^b indicate the top edges of the wing blades 12 and 13. Said top edges are made flat or blunt, as shown in Fig. 7, and the opposite faces of the wing blades taper from said top edges toward their respective cutting edges 12^a, 13^a.

In driving my improved nail or spike, it is placed with its point 14 against the surface of the piece or block of wood into which it is to be driven and with the spiral wing blades 12 and 13 arranged substantially parallel to the wood fibers. Thus the wing blades, when driven into the wood, tend to split the wood fibers apart to permit the entrance of the blades somewhat in the manner of a wedge, instead of splintering or breaking said fibers. As the nail is driven home, the spiral form of the wing blades 12, 13, causes the nail shank to rotate through a small angle so that said blades will assume a transverse position with ref-

erence to the wood fibers instead of the parallel position in which they started.

The wing blades 12 and 13 are twisted to such an extent that when the nail is driven home, that is to say, is driven a distance substantially equal to its length, said wing blades will cause the nail to turn through about a quarter of a revolution so that said blades will stand in a position substantially 10 at right angles to the wood fibers (see Fig. 5). In reaching this position, the cutting edges 12^a, 13^b of the wing blades 12, 13 cut their way through the wood fibers, so that the point of the nail reaches its final position 15 without materially splintering or distorting the wood fibers.

When the nail has been driven home, the top edges 12^b, 13^b of the wing blades, standing transversely of the wood fibers, as they 20 do, and being flat or blunt as heretofore described, resist any effort to withdraw the nail and thus securely anchor the same in the wood in the same manner as would a rivet head where a nail is driven through 25 a piece of wood and then riveted upon the opposite side.

Manifestly, the wing blades 12 and 13 need not be placed at the point of the nail or spike, but the arrangement at the point 30 of the nail or spike, as shown in the drawings, is preferred, as when placed in this way, they facilitate the entrance of the point of the nail or spike between the wood fibers to eliminate the splintering or breaking of 35 said fibers when the spike or nail first enters the wood.

The nail or spike head 11 is preferably made of a diameter such that it will project beyond the plane of the two wing blades 12, 13, as clearly shown in Figs. 4 and 5. Thus when the nail or spike is driven home,

the head 11 will completely cover the opening between the wood fibers produced by the wings in entering the wood. Said head thus acts to protect said opening from the entrance of moisture which would otherwise rust the spike or nail.

The advantages of my improvement and its applicability to nails and spikes used for various purposes where the nail or spike 50 is to be securely anchored in order to efficiently perform its intended function will be manifest to those familiar with the art.

I claim as my invention:

1. A spike comprising a shank, one end of 55 which is provided with diametrically opposed spiral blades projecting laterally beyond said shank, said blades having sharpened edges which converge toward and meet each other to form a driving point, said 60 blades being flat or blunt at the top, the other end of the shank being formed to provide a head.

2. A spike comprising a shank, one end of 65 which is provided with diametrically opposed spiral blades projecting laterally beyond said shank, said blades having more or less sharpened edges which converge toward and meet each other to form a driving point, said 70 blades being flat or blunt at the top, the other end of said shank being formed to provide a head, of a diameter greater than the combined width of said blades.

In testimony that I claim the foregoing 75 as my invention I affix my signature in the presence of two witnesses, this 10th day of April A. D. 1914.

CHARLES E. MARTIN.
